UNITED STATES PATENT OFFICE.

OSCAR L. WARD, OF EAGLE, NEBRASKA.

SLIDE-VALVE FOR ENGINES.

SPECIFICATION forming part of Letters Patent No. 434,367, dated August 12, 1890.

Application filed April 4, 1890. Serial No. 346,546. (No model.)

To all whom it may concern:

Be it known that I, OSCAR L. WARD, of Eagle, in the county of Cass and State of Nebraska, have invented a new and Improved 5 Slide-Valve for Engines, of which the following is a full, clear, and exact description.

The object of the invention is to provide a new and improved slide-valve for steam-engines which is simple and durable in construction and perfectly counterbalanced, so as to reduce the wear to a minimum.

The invention consists of a valve provided with intersecting slots.

The invention also consists of certain parts 15 and details and combinations of the same, as will be hereinafter fully described, and then pointed out in the claims.

Reference is to be had to the accompanying drawings, forming a part of this specification, 20 in which similar letters of reference indicate corresponding parts in all the figures.

Figure 1 is a plan view of a steam-engine provided with the improvement. Fig. 2 is a transverse section of the same on the line *x x* 25 of Fig. 1. Fig. 3 is a sectional plan view of the same on the line *y y* of Fig. 2. Fig. 4 is a rear sectional elevation of the same on the line *z z* of Fig. 3, and Fig. 5 is a perspective view of the slide-valve.

30 The engine A, to which the slide-valve is applied, is provided with the cylinder B, in which operates the piston C, connected in the usual manner with the main driving-shaft D. From the ends of the cylinder B lead the two 35 inlet-ports *a* and *b*, opening into the steam-chest E, in which is fitted to slide the valve F, actuated by suitable means from the main driving-shaft D. The slide-valve F is provided with a vertically-arranged slot *c*, connecting at its upper end at all times with the steam-inlet pipe G. The slide-valve F is also provided with a transversely-arranged slot *d*, intersecting the slot *c* at right angles and adapted to be connected alternately with the 40 steam-inlet ports *a* and *b*. The steam-chest E is also provided near each end with the exhaust-ports *e* and *f*, leading to the outside, and the ends of the cylinder B are also connected with the exterior of the steam-chest 45 50 E by pipes H and I, respectively opening into the said steam-chest in line with the respective ports *a* and *b*.

The operation is as follows: When the piston C and the valve F are in the position shown in Fig. 3, live steam passes through the inlet-pipe G into the vertically-arranged slot *c*, from which the steam can pass to the top and bottom of the slide-valve, so as to exert an equal pressure on the top and bottom. The live steam also passes into the transversely-extending slot *d*, so as to exert a pressure at each side, thus completely counterbalancing the valve, so that it only rests by its own weight in the bottom of the steam-chest E. The live steam passing into the slots *c* and *d* can pass from the latter slot through the inlet-port *a* into the outer end of the cylinder B, to exert its pressure against the piston C, in order to force the same inward in the direction of the arrow *a'*. The steam in the inner end of the cylinder B can now exhaust through the port *b*, leading into the steam-chest E, which is open at this end to the exhaust-port *f*, through which the exhaust-steam can escape. When the piston C nears the end of its inward stroke, the valve F changes its position—that is, it moves inward—so as to disconnect the transverse slot *d* from the inlet-port *a* to connect the said transverse slot *d* with the inlet-port *b*. At the same time the inlet-port *a* opens into the right-hand end of the steam-chest E, containing the exhaust-port *e*. Now live steam passing into the slots *c* and *d* passes into the port *b* to the inner end of the cylinder, to exert its pressure against the piston C to force the latter outward in the inverse direction of the arrow *a'*. The exhaust-steam in the outer end of the cylinder B passes through the port *a* to the outer end of the steam-chest E and through the exhaust-port *e* to the outer air. It will be seen that during the time the steam cuts off either the port *a* or *b* at the ends of the valve F pressure is exerted through the respective inlet-ports *a* or *b* against the cutting-off end of the valve F by the expanding steam in the cylinder; but this pressure against the valve F is counterbalanced by the steam in the cylinder passing from the respective pipe H or I against the cutting-off end of the valve F opposite the said port *a* or *b*. Thus it will be seen that the valve F is at all times completely counterbalanced, so that the weight is reduced to a minimum. It will further be

seen that the valve is very simple in construction and can be readily applied to all classes of engines.

Having thus fully described my invention, I claim as new and desire to secure by Letters Patent—

1. A slide-valve provided with a slot extending through it from top to bottom and with a second slot extending through it from side to side and intersecting the first-named slot, substantially as described.

2. The combination, with a cylinder provided with inlet-ports and a steam-chest into which the said ports open, of a slide-valve in the steam-chest provided with a slot extending through it from top to bottom and registering at all times with the inlet of the steam-chest, and with a second slot extending through it from side to side and intersecting the first-named slot, the said second slot alternately registering with the cylinder-ports, substantially as herein shown and described.

3. The combination, with a cylinder pro-

vided with inlet-ports, of a steam-chest held on the said cylinder and into which open the said ports, a slide-valve fitted to slide in the said steam-chest, and pipes connecting the ends of the said cylinder with the said steam-chest opposite the entrance of the said inlet-ports to equalize the cylinder-pressure on the said slide-valve when the ports are cut off, substantially as shown and described.

4. In a slide-valve, the combination, with a cylinder provided with inlet-ports and a steam-chest into which the said ports open, of a slide-valve in the steam-chest having intersecting slots extending through it at right angles to each other, and pipes connecting the ends of the cylinder with the steam-chest opposite the inlet-ports of the said cylinder, substantially as herein shown and described.

OSCAR L. WARD.
